LOGGING SHALES

Donald C. Bond, Crystal Lake, Ill., assignor to The Pure Oil Company, Chicago, Ill., a corporation of Ohio

No Drawing. Application August 2, 1951,
Serial No. 240,058

4 Claims. (Cl. 23—230)

This invention relates to a method of logging wells and particularly to a method of producing a well log by plotting the cation exchange properties of the clay content of the subsurface strata against the depth at which the particular formation is found.

In the constant search for petroleum bearing formations and optimum means for extracting the petroleum content of these formations, it is essential that as much information as possible concerning the nature of the strata lying beneath the surface of the earth be available. One of the most important problems confronting the subsurface engineer is the necessity of determining the same geological formation in each of several wells. In order to thus correlate these geological formations from well to well, accurate data delineating one formation from another and recognizing the same formation in the wells, regardless of extraneous conditions, must be available. Of perhaps equal importance is the problem of determining whether the area in which an exploratory well is being drilled is a productive one and, if it is, whether the well is properly located. This problem can often be solved by a study of the characteristics of the formations traversed by a bore hole, thus eliminating unnecessary drilling in areas devoid of petrolierous formations. In addition, in areas where water-drive is contemplated as a secondary recovery method it is desirable to know the nature of the formation to be flooded in order to obtain optimum results from the operation. Knowledge of the nature of a particular formation is also highly valuable in cases in which the permeability of the formation is to be increased by chemical treatment, such as acidizing.

Much of the information necessary for a proper evaluation of the characteristics of the subsurface strata of the earth is now supplied by the well log, produced by observing certain properties, physical, chemical, or the like, of the various strata forming the wall of the well bore and plotting these properties on a graph showing the depth at which the formation having the particular property selected is located. However, there is much valuable information regarding the nature of the subsurface formations which known methods of logging do not supply, the results obtained by these methods are often obscured by extraneous conditions brought into play by the methods of drilling utilized, and the data produced by conventional logging is often indistinct and incapable of accurate interpretation even by the most proficient observer.

It is accordingly an object of this invention to provide a method of logging bore holes which can be used to correlate strata among a number of related wells.

A further object of this invention is to provide a method of logging bore holes which will effectively recognize the same strata in a series of wells.

A further object of this invention is to provide a method of logging bore holes which will effectively recognize the same strata in a series of wells regardless of

2

the conditions of environment surrounding the formation in each well.

It is a further object of this invention to provide a method of logging bore holes which is unaffected by the conditions under which the well is being drilled.

A further object of this invention is to provide a method of logging bore holes which is unaffected by the drilling fluid being used in the drilling operation.

A still further object of this invention is to provide a method of logging bore holes which is unaffected by the degree of drilling fluid flushing employed in the drilling operation.

A further object of this invention is to provide a method of logging bore holes which is highly sensitive to changes in subsurface formations.

A still further object of this invention is to provide a method of logging bore holes which will clearly distinguish one formation from another.

Another and further object of this invention is to provide a method of logging bore holes which will supply information concerning the strata traversed by a bore hole which has not been available heretofore.

Another object of this invention is to provide a method of logging bore holes which will supply information concerning the history of the formations traversed by a bore hole.

Still another object of this invention is to provide a method of logging bore holes which will supply information concerning the conditions under which a shale was laid down.

It is another object of this invention to provide a method of logging bore holes which will supply information concerning the environment in which a subsurface strata was laid down.

Another object of this invention is to provide a method of logging bore holes which will supply information regarding the effect which a proposed reservoir treatment will have upon a formation to be treated.

Another object of this invention is to provide a method of logging bore holes which will supply information regarding the effect which a water flooding operation will have on the formation flooded.

Still another object of this invention is to provide a method of logging bore holes which will supply information regarding the effect which a well acidizing treatment will have on the formation treated.

Other and further objects of this invention will be apparent from the following description of my invention.

In accordance with my invention it has been found that the above objects can be accomplished by collecting samples of the subsurface strata forming the walls of a bore hole, determining the cation exchange properties of these samples, and correlating these values with the depth from which each sample was obtained to produce a log of the well.

The cation exchange properties of the clay content of an earth sample, adverted to here, include cation exchange capacity and concentration of exchangeable cations.

Cation exchange capacity, as used in this specification and the appended claims, denotes that capacity of a clay material which enables the clay to give up certain positively charged atoms or radicals and in turn adsorb other positively charged ions from among the elements and compounds existing in its environment. By exchangeable cations is meant those positively charged atoms or radicals which, because of their peculiar connection to a parent clay molecule or crystal, are capable of being replaced by other cations, under a given set of conditions, by virtue of the phenomenon of cation exchange.

The total cation exchange capacity of a clay-containing sample of earth is a fixed property of the clay. For example, a kaolin type clay will have a low cation exchange capacity while a bentonite type clay will have a high cation exchange capacity. Thus, the cation exchange capacity of an earth sample can be used to characterize a given clay and distinguish it from another clay having a different exchange capacity.

A significant feature of the cation exchange capacity of a clay is that this property can be changed only if the clay is subjected to rather severe conditions such as prolonged heating with strong acid or strong caustic solution. This point is important in producing a log of a well bore due to the fact that a large variety of drilling fluids are used in the drilling operation to reduce friction and aid in carrying drill cuttings from the hole to the surface. If a water-base drilling fluid is utilized there is a strong possibility that the sample of strata to be examined will be invaded by water. As a result of the unchanging character of cation exchange capacity, this invasion of the strata sample will not interfere with measurements of the exchange capacity of the sample. This is true regardless of the type of drilling fluid used and the degree to which the well is flushed with drilling fluid.

Another distinct advantage of the property of cation exchange capacity is that this property is unchanged by the replacement of exchangeable cations by substances in contact with the strata. By the replacement of exchangeable cations of an earth sample the kind of exchangeable cations in the sample are changed but the total cation exchange capacity remains constant. For example, the aluminum ion of an aluminum chloride solution will displace exchangeable sodium from a clay practically quantitatively but the exchange capacity of the clay is unaltered. From this it may be seen that the use of a drilling fluid containing a compound capable of exchanging cations with the clay, such as the ability of a lime-base fluid to exchange calcium for sodium adsorbed on the clay, will change the kind of cation adsorbed but not the total cation exchange capacity of the clay sample. In addition, a clay of uniform composition might be laid down over a given area followed by invasion of part of the area by water that contains cations capable of replacing the adsorbed ions on the clay, for example, calcium for sodium. This invasion of the clay would change the kind of exchangeable cations adsorbed on the clay but would not change its cation exchange capacity. Therefore, by measuring the cation exchange capacity of clay samples from wells drilled in both the invaded and uninvaded areas, this clay, which is common to both areas, would be recognized as contemporary.

A clay deposited over a considerable area during a given period of sedimentation will have the same cation exchange capacity throughout the whole area. By producing a log of the cation exchange capacity of the strata traversed by a bore hole a pattern that should be duplicated in neighboring wells results, and the strata may thus be correlated over the area.

It may be seen from the above that the method of logging comprising my invention will permit correlation of strata from well to well regardless of the drilling fluid used, invasion of the area by water, or other extraneous conditions.

In contradistinction to the method of logging of my invention, the electrical log and other known methods of logging make little distinction between one shale and another. For example, an electrical log may show the same electrical specific resistivity for two entirely different subsurface formations, and the log is often influenced by the character of the drilling fluid used and the thickness of the film of drilling fluid on the wall of the bore hole. Methods of logging employing chemical analysis are also subject to serious disadvantages. For example, clays of identical chemical composition may have different cation exchange capacities and clays of the same

cation exchange capacity may have different chemical compositions.

If an earth sample were merely analyzed for its content of a given cation, such as calcium, this analysis would result in an erroneous conclusion as to the type of formation present. This analysis for calcium would be influenced by the type of drilling fluid used in the well or by the invasion of the area by a water containing calcium or other compounds containing exchangeable cations. For example, a lime-base mud would exchange calcium for sodium of the clay sample and would thus result in a high concentration of calcium cation which was not present in the original sample. Likewise, the invasion of the formation by a calcium containing water would also exchange calcium ions for sodium and thus alter the characteristics of the earth sample. From this it follows that a chemical analysis of an earth sample would be influenced by the type of mud used in drilling, by the degree of drilling fluid flushing, or by the invasion of the area by water containing calcium compounds. The analysis of the earth sample for cation exchange capacity would be influenced by none of these extraneous conditions, and this method would recognize a clay laid down during a given period of sedimentation as being contemporaneous regardless of the conditions surrounding the drilling of the well or the environmental changes occurring after the clay was laid down.

An additional advantage of the determination of cation exchange capacity of an earth sample is the sensitivity of this method. This arises from the fact that the cation exchange capacity of a clay may vary from 1 to about 125 milliequivalents per 100 grams depending upon the type of clay present. At the same time, the $\text{SiO}_2/\text{R}_2\text{O}_3$ (where R represents Al or a complex mixture of Al and Mg, K, or other metals) ratio of the clay could vary only through the range of about 1:1 up to 4:1. Thus the cation exchange capacity of a clay is a very sensitive indicator of differences in types of clays.

The determination of the concentration of exchangeable cations on an earth sample enables one to obtain much valuable information concerning the history of the formation and the environment in which the formation was laid down. A clay deposited in one environment will contain different adsorbed cations than a clay laid down in another environment. For example, a clay deposited in a fresh, hard water environment will have calcium as the predominating adsorbed cation. On the other hand, a clay deposited in a strong brine environment will contain sodium as its predominating cation. Also, if strontium is present in the water in which a clay settles, strontium will be found adsorbed on the clay. By determining the concentration of exchangeable cations in an earth sample it is thus possible to use one of these exchangeable cations as a marker to follow the particular formation over the area in question. Since the marker selected, such as strontium, will be widely and uniformly distributed over a given area, a valuable means for correlating formations in a series of related wells is provided.

In addition to the value of a log of exchangeable cations for correlation purposes, these logs will also be of value in investigations of the substrata in an exploratory well. Knowing that petrolierous deposits are often found in formations laid down in a brine environment, the presence of a high concentration of exchangeable sodium in a formation sample will indicate that a petroleum bearing formation will be located either above, below, or laterally displaced from the point at which the sample was taken.

The adsorbed ions on an earth sample also give valuable information concerning the history of the shale. For example, passage of water from an organic reef, containing strontium, through the shale would result in the adsorption of the strontium by the shale. Therefore, the presence of strontium in the shale as an adsorbed cation

should indicate the presence of an organic reef near the shale from which the sample was extracted.

Clay minerals are found in sands and sandstones as discrete particles mixed with the quartz grains and as a film plastered around the quartz grains. Due to the crystalline structure of the clay, structural changes often occur when water is passed through the clay. For example, if a sand contains small amounts of montmorillonite clay having calcium present as the predominating exchangeable cation, the passage of water containing sodium through the sand would cause the sodium to replace calcium in the clay. The result of this exchange would be the separation of the individual flakes, a splitting of discrete clay particles, and an unplastering of the quartz grains. The net result would be the liberation of minute clay mineral particles and a plugging of the sand by these particles. On the other hand, if the montmorillonite carried sodium as the predominating exchangeable ion, there would be little or no exchange of cations and little clogging. Therefore, if a water flooding operation is contemplated, it would be desirable to know the character of any clay component in the sand and the nature and concentration of exchangeable cations in the clay in order to determine the type of water to use for flooding or to select proper methods of pretreating a water to be used. A log of the exchangeable cation concentration of such a well would thus furnish the information necessary for obtaining optimum results from a proposed flooding operation.

The structural changes in the character of a clay are not confined to changes brought about by contact with waters containing various compounds. Certain structural changes occur when an acid solution, such as hydrogen chloride, contacts a formation containing a clay. Clays existing in a productive limestone or dolomite formation may occur enclosed by the limestone or dolomite or in fractures and flow channels of the formation. When an acid solution, such as HCl, contacts such a formation the hydrogen of the HCl will replace cations adsorbed on the clay. This exchange of cations results in a flocculation or a decrease in volume of the clay particles. However, as the HCl attacks the limestone formation calcium is liberated and as it attacks a dolomite formation calcium and magnesium are liberated. Concurrent with this liberation of calcium and magnesium the reaction of the acid on the formation also changes the pH of the acid solution and in turn the pH of the environment of the clay. As the pH of the environment of the clay is altered an exchange of calcium and magnesium for the hydrogen adsorbed on the clay takes place. The net results of this exchange of cations and the concomitant change in pH of the environment of the clay is to cause the clay to swell and thus tend to neutralize the increase in formation permeability brought about by the acidizing treatment. By studying the log of a bore hole produced by the method of my invention the type of clay present and the amount of exchangeable cations present can be determined and a proper anti-swelling agent may be selected for addition to the acidizing solution.

In the practice of my invention, samples of the substrata are collected at spaced intervals in the bore hole. These samples may be those secured with a conventional vertical core barrel or side coring device or they may be cuttings from the drill bit which are brought to the surface by the circulation of the drilling fluid. The methods of determining the depth from which these samples are collected are also well known in the art and form no part of my invention. The cation exchange capacity and the kinds and amounts of exchangeable cations are then determined for each sample. There are several known methods of determining the cation exchange capacity and concentration of exchangeable cations of a clay sample. However, I prefer to utilize the normal NH₄Cl method. This method consists of shaking 25 grams of dry, pul-

verized sample with 250 cc. of normal NH₄Cl neutralized to pH 7 with NH₄OH, transferring the sample to a filter, and leaching with normal NH₄Cl, prepared as above, until the last portion of the effluent from the leaching gives no test for calcium or other cation besides NH₄⁺. The effluent is then analyzed for its content of exchangeable cations (calcium, magnesium, strontium, potassium, sodium, etc.), as well as NH₄ ion. The amount of NH₄ ion found in the solution subtracted from the NH₄ ion content of an equal volume of the original NH₄Cl solution is equal to the cation exchange capacity of the sample. This measurement of the amount of exchangeable cations replaced by NH₄ ion should check with the sum total of individual cations as determined by analysis of the effluent from the leaching. If a sample contains calcium carbonate or other soluble or decomposable substances and the concentration of exchangeable calcium is to be determined, this procedure may be varied slightly to correct for the calcium dissolved by the leaching procedure from the calcium carbonate present in the sample. This correction is obtained by determining the calcium carbonate content of the sample before and after leaching, and then subtracting from the calcium found in the effluent from the leaching, an amount of calcium equivalent to calcium carbonate dissolved. Other methods of determining the cation exchange capacity and the concentration of individual exchangeable cations of the sample may be carried out and the above test is not to be considered a limitation upon the invention described herein.

After the values of cation exchange capacity and exchangeable cations have been obtained, as set forth above, a log of the well is prepared by plotting these values versus the depth from which each sample was obtained.

Summarily, it can be seen that the log prepared by the method of my invention may be used for the correlation of subsurface strata over a given area by matching the strata having the same cation exchange capacity in each of several wells or by following an individual exchangeable cation through the subsurface formation.

The log produced by the method of my invention may also be used to determine the environment under which a given clay was laid down. That is, it may be determined whether a clay was laid down in an ordinary fresh water environment or in a marine environment.

My method of logging also enables the subsurface engineer to obtain information concerning the history of subsurface formations. Clay laid down during a given period of sedimentation followed by the passage of water from an organic reef, containing strontium, through the shale would indicate the changes in environment which had taken place subsequent to the time the clay was laid down.

An additional use of the log prepared by the method of my invention is the determination of the characteristics of formations which are to be water-flooded. Knowing the concentration of exchangeable cations in the formation, the proper water to use in a flooding operation can be selected or a given water may be treated accordingly. Thus undesirable plugging of the flooded formation may be avoided.

Further, the method of logging of my invention can be used to determine the type of clay present and the character of the exchangeable cations of such clay as a preliminary to a proposed acidizing treatment. In view of the type of clay present and the exchangeable cations of the clay, as determined by a study of my well log, a proper acidizing solution may be selected and proper control of the environment in the formation can be maintained in order to obtain optimum results from an acidizing treatment.

It will be apparent that no attempt has been made to describe all the possible types of formation sampling which may be practiced in carrying out my invention or all types of tests which may be employed in analyzing

these samples. It will be understood that my invention is not to be limited to a particular method of collecting samples or analyzing these samples, but contemplates broadly any procedure by which samples of subsurface strata are collected and tested to determine their cation exchange capacity and the concentration of exchangeable cations present and correlating these values with depth to produce a well log.

The nature and objects of my invention having been described and illustrated above, what is claimed as new and useful and is desired to be secured by Letters Patent is:

1. A geophysical well logging process for determining the characteristics and position of clayey strata containing exchangeable cations in the clayey constituents of the strata which comprises collecting samples of said clayey strata at spaced intervals along a bore hole, leaching each of said samples with a solution containing a replacing cation not present in the clayey constituents of the strata to produce from each sample an effluent whereby all of the exchangeable cations in each of said samples are substantially completely replaced by said replacing cation and are contained in said effluent, thereafter determining the amount of replacing cation which is adsorbed by each of said samples whereby the total cation exchange capacity of each sample is ascertained, analyzing the effluent from each sample to quantitatively and qualitatively identify at least one of the exchangeable cations contained in each sample, and preparing a well log by correlating the total cation exchange capacity value of each sample and the determinations of the aforesaid qualitative and quantitative analysis of the effluent from each sample with the position in the well bore from which the sample was obtained.
2. A process in accordance with claim 1 in which the replacing cation contained in said solution is NH_4^+ .
3. A process in accordance with claim 1 in which the total cation exchange capacity is obtained by quantitatively analyzing said effluent for the amount of replacing cation derived from said solution contained therein whereby the total cation exchange capacity of each sample may be determined.
4. A geophysical well logging process for determining the characteristics and position of clayey strata contain-

ing exchangeable cations in the clayey constituents of the strata which comprises collecting samples of said clayey strata at spaced intervals along a bore hole, comminuting each of said samples to produce a plurality of samples each having substantially the same particle size, leaching each of said samples with an ammonium chloride solution to produce an effluent from each of said samples whereby all of the exchangeable cations in each sample are substantially completely replaced by the NH_4^+ cation contained in said solution and are contained in said effluent, determining the amount of NH_4^+ cation adsorbed by each of said samples, whereby the total cation exchange capacity of each sample is ascertained, quantitatively and qualitatively analyzing the effluent from each of said samples to determine the exchangeable cations contained therein and preparing a well log by correlating the total cation exchange capacity value of each sample, and the determinations of the aforesaid qualitative and quantitative analysis of the effluent from each sample with the position in the well bore from which the sample was obtained.
